Specification of Letters Patent.

Patented Oct. 29, 1912.

Application filed October 12, 1911. Serial No. 654,360.

To all whom it may concern:

Be it known that I, SIDNEY MARTIN, a subject of the King of Great Britain, residing at Chelsea, in the county of Suffolk and State of Massachusetts, have invented certain new and useful Improvements in Suspenders, of which the following is a specification, reference being had therein to the accompanying drawing.

10 This invention relates to suspenders intended to be used by men engaged in severe manual labor, and has for its object the production of a simple and efficient means whereby elastic strips may be connected to the nonelastic portions of the suspenders without causing any roughened or enlarged places upon the body engaging faces of the suspenders.

Another object of this invention is the 20 production of a suspenders, the straps of which are formed from a woven tubular cotton seamless web thereby forming a strong strip without having any folded portions for wearing against the body.

25 In the drawings:—Figure 1 is a plan view of the back of the suspenders. Fig. 2 is a plan view of the under side of the suspenders. Fig. 3 is a longitudinal section through the strap carrying the loop strap. Fig. 4 is a transverse section taken through one of the strips from which the suspenders are made showing the two sides flat or in their normal position. Fig. 5 is a transverse section through one of the straps showing 30 the sides bulged to more clearly bring out the construction of the straps. Fig. 6 is an enlarged longitudinal sectional view taken through one of the straps showing 35 whereby the elastic means are attached to the tube straps.

The suspenders consist of two cross front straps 1 and rear tabs 2, which tabs are connected to the front straps 1 by means of elastic strips 3. One of the front straps 1 is provided near its rear end and upon its outer face with a loop-strap 4 which crosses the other front strap as illustrated in Fig. 1 for holding the two members of the suspenders together. The rear tabs 2 are provided with button holes 5 for allowing the rear tabs to be connected to the rear of the trousers and the front straps carry at their forward ends button engaging clips 6 of any desired construction. The button holes 5 are barred or stitched zigzag across their edges so as to do away with the necessity of

turning the edges under to form a smooth edge. The straps 1, as well as the tabs 2 are formed from a woven tubular cotton seamless web so as to do away with any 40 rough places appearing upon the strips or tabs whereby the body of the wearer will be rubbed, as usually occurs with the ordinary suspenders wherein two strips are used to form the sections of the suspenders and are 45 stitched along their edges. An elastic strip 3 as previously described is interposed between the front members 1 and the tabs 2, and has its ends placed between the side walls of the tubular portion out of which the strap and tabs are made. The edge of the tabs 2 and straps 1 are barred or stitched zigzag so as to form a smooth surface along 50 the edge of the straps or tabs and also firmly hold the elastic in engagement with the ends 55 of the straps 1 and tabs 2. By having the elastic strips attached to the tubular seamless webs as just described, it will not be necessary to turn the edges of the seamless webs under for forming a neat edge and preventing the webs from unraveling for the 60 threads being zigzag or barred as is commonly termed will form an efficient binding or trimming for the edge of the seamless webs, and the barring is so constructed as to 65 cause the heaviest part of the stitching to appear upon the top of the suspenders thereby forming a substantially flush under 70 face along the entire length of the section 75 of the suspenders. The end of the loop-strap 4 is secured to the front strap 1 by a 80 row of barred stitching 7, in the same manner as described in connection with the securing means of the straps with the elastic strips. The lower ends of the rear tabs 2 85 have their edges folded under slightly and are barred in the same manner as described 90 in connection with the elastic strips and the straps 1 of the suspenders.

95 From the foregoing description it will 100 be obvious that an efficient suspender has been produced whereby a smooth under surface will be presented for allowing the same to be worn with ease. It is very undesirable to wear suspenders which are provided with the slightest portion which may be likely to rub upon the body, especially where the suspenders consists of a pair of strips secured together along their outer edges. The present invention is, therefore, especially adapted 105 to be used in connection with cheaply made suspenders preferably formed or man-

manufactured from the ordinary overall material, and by the construction of the suspenders in the manner as above specified not only a saving will be effected for the manufacture, but also an efficient suspender will be produced without having any parts which might rub upon the body and thereby cause chafing.

Having thus described the invention what is claimed is:

A button tab formed of a tubular web, the outer end of said web having its edges turned in and stitched together with barred stitching, a strap inserted into the inner end

of the tubular web and secured thereto with barred stitching, and a button hole formed by cutting through both plies of said tubular web and stitched around with barred stitching for preventing any rough places appearing upon the suspenders which would be likely to rub upon the wearer's body.

In testimony whereof I hereunto affix my signature in presence of two witnesses.

SIDNEY MARTIN.
